[57] CLAIM

The ornamental design for handle, as shown and described.

DESCRIPTION

FIG. 1 is a perspective view as seen from the top, front, and left side of a handle showing my new design;

FIG. 2 is a perspective view of the handle in an upside-down position and seen from the bottom, front, and right side thereof;

FIG. 3 is a front elevational view thereof;

FIG. 4 is a right side elevational view thereof, the left side elevational view being a mirror image of the right side elevational view;

FIG. 5 is a top plan view thereof; and,

FIG. 6 is a bottom plan view thereof.
